BOOK SIGNATURE FEEDING METHOD

Carl Schramm, North Coventry, Conn., assignor
to Smyth Manufacturing Company, Hartford,
Conn., a corporation of Connecticut

Application March 13, 1944, Serial No. 526,144

7 Claims. (Cl. 270—54)

Book signatures commonly comprise sheets of paper right-angularly folded, that is, folded across what is to be the top or head of the book and folded across what is to be the back of the book. In assembling into book form the signatures are opened at the middle and deposited on a support or saddle from which they are fed to a stitching or stapling machine that secures together the folded back edges. Subsequently the folded head edges and front edges are trimmed.

Ordinarily at the front of the first and the back of the last signature are end-leaves or sheets for the attachment of the cover. Sometimes illustrating or advertising plates are placed between the front end-leaves and main signature leaves. The end-sheets have single folds that are pasted along the back edges of the adjacent signature leaves and often times the end-leaves and plates are of heavier stock than the other signature leaves.

The invention is illustrated and described herein as adapted to signature feeding machines of the type disclosed in Patents Nos. 2,025,527, dated Dec. 24, 1935, and 2,124,862, dated July 26, 1938, and reference is made thereto for an understanding of the operating mechanisms.

In the prior machines the signature is fed to a rotating cylinder and by it carried around with its folded back edge in advance, until it hangs vertically. When in this position suction cups swing upward and inward from opposite sides and grasp the end-leaves near the unfolded lower or front book edge, and then swing downward and outward so as to draw the signature from the cylinder and pull it open. When opened the suction of the cups on the end-leaves is released and the signature allowed to drop onto the support or saddle.

As the end-leaves are folded only at the back edges, the other edges being free, it sometimes happens that, particularly if the end-leaves are of heavier stock than the other leaves or a plate is interposed, the suction cups fail to draw the signatures completely open at the middle. The object of the present invention is the provision of a simple method and means which can be operated at high speed with the assurance of a complete opening of the signatures at their middle so that they will be accurately deposited on the support or saddle in proper condition for subsequent treatment, and thereby eliminate the above mentioned possibility of failure of the signatures to be properly opened.

Figure 1 of the accompanying drawing illustrates a signature brought to vertical position by

the feed cylinder and grasped by the suction cups. Fig. 2 shows the signature partly opened by the action of the suction cups. Fig. 3 shows the signature fully opened above the saddle. Fig. 4 is a face view of the signature showing the end-leaves punctured in one manner. Fig. 5 shows the end-leaves punctured in a different place. Fig. 6 shows a modified form of holes in the end-leaves. Fig. 7 illustrates the position of the suction cups against the face of the end-leaves. Fig. 8 illustrates the relation of the suction cups to the signature, on exaggerated scale. Fig. 9 is a view showing a means for puncturing the end-leaves.

10 15 20 25 30 35 40 45 50 55

In the drawing 1 indicates the continuously rotated signature feed cylinder, 2 a signature, 3 suction cups, 4 the ends of the tubes which lead from the cups to a valve controlled means for producing the required suction at the proper time, 5 the ends of arms which carry the suction cups up and in for grasping the signature, and drawing it down and out for opening the signature above the saddle 6.

Fig. 8 is a sectional view taken near the folded head end of a signature, on exaggerated and distorted scale, showing the relation of the main or inner leaves 7 of a signature and the end-leaves 8, of heavier stock, grasped by the suction cups. The end-leaves are shown as having perforations 9 that are spanned by the cups. As a result of this condition not only will the end-leaves be drawn out by the pull of the suction cups but also, as the cups span the perforations, the folded head ends of the inner signature leaves 35 will be pulled apart and separated at the middle so that the signature will drop accurately on the saddle.

The perforations in the end-leaves can be positioned along the head edge 10, as shown in Fig. 4, or along the front edge 11, as shown in Fig. 5, or both, or the edges may be mutilated by notches 12, as shown in Fig. 6. The perforations or notches are located near to or at the edges of the end-leaves so as to be removed when the signature is trimmed, as indicated by the dotted lines 13, and they may be made by passing the end-leaves between rolls 14 provided with punches or cutters 15, Fig. 9.

The simple conception of perforating or cutting 50 away edges of the end-leaves and exposing portions of the inner leaves near their folded edges is applicable to high speed signature feeding mechanisms employing suction means for opening the signatures, as not only are the free front edges of the end-leaves drawn open by the suc-

tion means, but regardless of the thickness of the end-leaves, the inner leaves of the signature are drawn apart at the middle, for they are subject to the pull of the suction means which span the removed portions of the end-leaves and the exposed portions of the inner leaves near their folded edges.

The invention claimed is:

1. The method of opening book signatures that have folded body leaves and end leaves, which comprises mutilating the end-leaves of the signatures by cutting away or perforating them at or near their edges outside of the trim lines of the signatures, and subjecting the end-leaves and the signature leaves inside of said mutilations, coincidently to the pull of suction means.
2. The method of opening folded book signatures that have unfolded end leaves, which comprises removing small portions of the end-leaves of the signature outside of the trim lines of the signature and simultaneously subjecting the end-leaves and the signature leaves inside of the removed portions of the end-leaves to the pull of suction means.
3. The method of opening book signatures that have folded body leaves and end leaves, which comprises perforating the end-leaves of the signatures near their edges, and applying suction producing means to said end-leaves over and about said perforations.
4. The method of opening book signatures that have folded body leaves and end leaves which

comprises perforating the end-leaves of the signatures near folded edges of the body leaves, applying suction means to the end-leaves over the perforations, and producing a suction in and drawing apart said suction means.

5. The method of opening book signatures that have folded body leaves and front and back end leaves, which comprises cutting openings through the front and back end-leaves near the folded

edges of the body leaves, moving suction means inward against the end-leaves so as to cover said openings, producing a suction in said suction means, and drawing said suction means and signature leaves outward.

15 6. The method of opening book signatures which have folded body leaves and attached end leaves and plates, that comprises perforating the end-leaves and plates, applying suction means to the end-leaves over said perforations and by said 20 suction means drawing the end-leaves, plates and body leaves of the signature apart at the middle of the body leaves.

7. The method of opening book signatures that have folded body leaves provided with end-leaves, 25 which comprises removing portions of the end-leaves so as to expose portions of the folded body leaves and applying suction to the end-leaves and exposed portions of the body leaves and simultaneously drawing open the end-leaves and the body leaves of the signatures.

30 CARL SCHRAMM.
